DISPLAY BOX

Samuel Braun, Rye, N.Y., assignor to B.C.N. Design
Products Inc., Amityville, N.Y., a corporation of
New York

Filed Jan. 9, 1967, Ser. No. 5,351

Term of patent 14 years

(Cl. D58—12.7)

FIG. 1

FIG. 7

FIG.3

FIG. 4

FIG. 5

FIG. 6

FIG. 1 is a three-quarter perspective view of a display box embodying my new design, the lid being shown in closed position;

FIG. 2 is a top plan view thereof;

FIG. 3 is a bottom plan view thereof;

FIG. 4 is a front elevational view thereof;

FIG. 5 is a rear elevational view thereof;

FIG. 6 is a side elevational view thereof; and

FIG. 7 is a three-quarter perspective view thereof with the lid in open position.

The dominant features of my design reside in the portions shown in full lines. The drawing is lined to indicate contrast.

I claim:

The ornamental design for a display box, as shown and described.
